(57) **CLAIM**

The ornamental design for a cam member, as shown and described.

DESCRIPTION

FIG. 1 is a front elevational view of a cam member showing our new design, a rear elevational view being a mirror image thereof;

FIG. 2 is a right side elevational view thereof;

FIG. 3 is a left side elevational view thereof;

FIG. 4 is a top plan view thereof;

FIG. 5 is a bottom plan view thereof; and,

FIG. 6 is a perspective view thereof.

Portions of FIGS. 1–6 that are shown as broken lines are for illustrative purpose only and form no part of the claimed design.
